UNITED STATES PATENT OFFICE.

HENRY REUBEL, OF NEW YORK, N. Y.

CURTAIN-FIXTURE.

965,658.

Specification of Letters Patent. Patented July 26, 1910.

Application filed October 25, 1909. Serial No. 524,374.

To all whom it may concern:

Be it known that I, HENRY REUBEL, a citizen of the United States, and a resident of the city of New York, borough of Manhattan, in the county and State of New York, have invented a new and Improved Curtain-Fixture, of which the following is a full, clear, and exact description.

The invention relates to curtain holders used for vestibule doors, windows and the like, and such as shown, for instance, in the Letters Patent of the United States, No. 891,622, granted to John Kroder, June 23, 1908.

15 The object of the invention is to provide a new and improved curtain fixture arranged to permit convenient attachment to the door or window, for attaching the curtain-supporting member in position on the keepers fixed on the door or window, and for removing the said members from the keepers with a view of placing the curtain in position or removing it therefrom.

20 For the purpose mentioned, use is made of a curtain-supporting member and keepers for receiving the terminals of the said member, the keepers being provided with means for pressing said terminals to clamp the same in position in the keepers.

25 A practical embodiment of the invention is represented in the accompanying drawings forming a part of this specification, in which similar characters of reference indicate corresponding parts in all the views.

30 Figure 1 is a perspective view of the improvement as applied; Fig. 2 is an enlarged perspective view of one of the keepers; Fig. 3 is an enlarged cross section of the fixture at one of the keepers; and Fig. 4 is a sectional plan view of the same.

35 The supporting member A for the curtain is preferably made of telescoping sections A¹, A², having angular end portions A³, A⁴ provided with flanges B, B' for sliding engagement with keepers C, C' fastened by screws D to a support E, such as a door or window.

40 Each keeper C, C' is preferably formed from a single piece of metal bent to provide a back C² and guideways C³ at the sides, for the sides of the flanges B, B' to slide in, from the open top in a downward direction, to engage the flange B or B' with the corresponding guideway, the downward movement of the flange B or B' being limited by a bottom C⁴ formed on each keeper.

45 Spring tongues C⁵ are struck up from the back C² of each keeper C, C', to engage and press the rear face of the corresponding flange B or B', so as to clampingly engage 60 this flange with the guideways C³, to securely hold the flange in position in the keeper. As shown in Fig. 2, the spring tongues C⁵ extend forwardly, approximately parallel with the guideways C³, and 65 the upper corners C⁶ of the flanges C⁵ are bent rearwardly, to permit of guiding the flange B or B' into position when inserting the flanges B, B' in the keepers C, C'.

70 In using the curtain fixture, the keepers C and C' are secured to the support E by the screws D which pass through apertures C⁷ in the back C², to screw in the support E, as plainly indicated in Fig. 3, and the curtain is placed on the section A¹ of the 75 curtain support A, after which the other section A² is telescoped with the section A¹, and then the flanges B and B' are inserted in the keepers C, C' from the top thereof, and pressed downward to engage the spring 80 tongues C⁵, which then press the flanges B, B' against the corresponding guideways C³ to lock the flanges B, B' in place in the keepers C, C'. By reference to Fig. 1, it will be noticed that when the flanges B, B' 85 are in position in the keepers C, C', the attaching screws D are completely hidden and a large bearing surface is provided for the flanges B, B', to securely hold the fixture in place, and to properly support the 90 curtain in position. When it is desired to remove the supporting member A and the curtain held thereon, it is only necessary for the operator to take hold of the ends A³, A⁴ and push the same upward to disengage the flanges B, B' from the keepers 95 C, C'.

95 The curtain fixture shown and described is very simple in construction, ornamental in appearance and arranged for convenient 100 and quick attachment to the door or window.

Having thus described my invention, I claim as new and desire to secure by Letters Patent:

1. A curtain fixture, comprising a curtain 105 supporting member having an angular flat plate flange at the end and a keeper for attachment to a support and formed of a single piece of sheet metal bent to form a back, guideways at the sides for the said 110 plate flange to slide in, a bottom for limiting the downward movement of the plate

flange, and a pair of spring tongues struck up from the said back and extending forwardly to engage and press the rear face of the said flat plate flange and clamp the same 5 in position in the guideways.

2. A curtain fixture, comprising a curtain supporting member having an angular flat plate flange at the end and a keeper for attachment to a support and formed of a 10 single piece of sheet metal bent to form a back, guideways at the sides for the said plate flange to slide in, a bottom for limiting the downward movement of the plate flange, and a pair of spring tongues struck 15 up from the said back and extending for-

wardly to engage and press the rear face of the said flat plate flange and clamp the same in position in the guideways, the said tongues extending from the said back sideways in opposite directions, and the upper 20 corners of the said tongues being bent rearwardly to guide the flange into position.

In testimony whereof I have signed my name to this specification in the presence of two subscribing witnesses.

HENRY REUBEL.
